(57) **CLAIM**

The ornamental design for a dispenser, as shown and described.

DESCRIPTION

FIG. 1 is a perspective view from the right of my new dispenser;

FIG. 2 is a perspective view from the left of my dispenser;

FIG. 3 is a bottom view of my dispenser;

FIG. 4 is a side view of my dispenser, with the opposite side

view of my dispenser being a mirror image thereof;

FIG. 5 is a top view of my dispenser;

FIG. 6 is a front view of my dispenser; and,

FIG. 7 is a rear view of my dispenser.

The broken lines in the drawings are for illustrative purposes only and form no part of the claimed design.
